UNITED STATES PATENT OFFICE.

JAMES D. NELSON, OF CINCINNATI, OHIO.

ELECTRIC SIGNAL SYSTEM.

1,403,561.

Specification of Letters Patent. Patented Jan. 17, 1922.

Application filed May 9, 1917. Serial No. 167,385.

To all whom it may concern:

Be it known that I, JAMES D. NELSON, a citizen of the United States of America, and resident of Cincinnati, in the county of 5 Hamilton and State of Ohio, have invented a new and useful Improvement in Electric Signal Systems, of which the following is a specification.

An object of my invention is to produce 10 an electric signal system particularly adapted for use with automatic fire extinguisher systems, which is capable of sending three distinguishable signals to indicate a flow of water through the extinguisher system, a 15 break in the circuit in which the supervised elements of the extinguisher system are located, and battery trouble.

This and other objects are attained in the 20 electric signal system described in the following specification and illustrated in the drawing in which the system is disclosed somewhat diagrammatically.

Fig. 1 is a diagrammatical view of a device embodying my invention, showing the 25 parts in their normal relation.

Fig. 2 is a diagrammatical view of the device shown in Fig. 1, showing a relation of the parts, in event of wire trouble.

Fig. 3 is a diagrammatical view of the device shown in Fig. 1 when the device is subject to battery trouble.

Fig. 4 is a diagrammatical view of an automatic sprinkler such as is supervised by the device shown in Fig. 1.

35 My improved system consists of a signal transmitter 1, a timing device 2 adapted to control the operation of the transmitter, an electromagnet 3 adapted to control the operation of the timing device, a battery 4 from 40 which energy for the operation of the system is obtained, and the necessary wiring for connecting the various elements of the system and the diagrammatically illustrated valve switches 5 which are adapted to be 45 closed upon change of condition within the fire extinguisher system.

The transmitter of my improved system 50 consists of a signal transmitting wheel 6 adapted to operate a signal sending key or switch 7 for sending a signal over the main line 8 to the central station where the signal is recorded, a disc 9 having notches 10 and 11 for cooperation with a tripping lever 12, a cam 13 for controlling the operation of 55 a switch 14, a cam 15 for controlling the operation of a switch 16, and an escapement

pawl and ratchet 17 and 18 respectively for controlling the speed of the transmitter. Disc 9 and cams 13 and 15 are shown mounted upon and secured to a shaft 19. Cooperating with disc 9 is a pawl 20 the end 21 of which is adapted to engage notches 10 and 11 at certain periods and under certain conditions, thereby controlling to some extent the operation of the transmitter. Pawl 20 is loosely mounted on pivot 60 and carries an arm 22 upon which is mounted a member 23 for engaging a branch 24 of a forked finger 25 which is secured to the pawl 17, the remaining branch 26 of the forked finger 70 being adapted to be engaged by a shoulder 27 of transmitter locking lever 12. An overhanging end 28 of locking lever 12 is adapted to cooperate with timing device 2 when the timing device is released by magnet 3 for 75 the purpose of lifting lever 12 to release the transmitter. Arm 22 of pawl 20 carries at its end a pin 29 adapted to engage the surface of a sector 30 secured to a pivotally mounted shaft 31 which also forms an element of the timing device. A lever 32 is secured to shaft 31 at a point between its ends and is provided at one end with an armature 33 adapted to be controlled by electromagnet 3 and at its opposite end is provided with a 80 weight 34 for lifting the armature and rotating shaft 31 and sector 30 when magnet 3 is deenergized. A gear 35, a pinion 36, and a fan plate 37 are provided for controlling the dropping motion of the weight 34. The 90 spring controlled pawl 38 is provided for engaging a ratchet 39 secured to gear 35 so that the weight 34 may be elevated quickly when magnet 3 is energized without operating the retarding fan 37 and will connect the 95 weight with the retarding fan when armature 33 is released by magnet 3. Switch 14 which in its normal condition closes the circuit through magnet 3 from battery 4, consists of switch arms 40 and 41 which are 100 adapted respectively to engage switch contacts 42 and 43. Switch 16 which is provided for closing an auxiliary circuit through magnet 3 when switch 14 is opened during certain operations of the transmitter, 105 consists of a switch arm 44 which is adapted to engage a contact 45, and a switch arm 46 which is adapted to engage a contact 47. The switches of the supervised devices 5, which are in the extinguisher system to be 110 supervised, and which are controlled by the opening and closing of the valves of the sys-

tem, consist of contacts 48 which are engaged by switch arms 49. The pipe 48^a is connected to the battery 4. A series of discharge or sprinkler nozzles 48^b are mounted upon the pipe 48^a and are sealed by means of a plug 48^c, such plug being of fusible metal. A bracket 48^d is mounted on the nozzle 48^b and has pivotally mounted upon it at pivotal point 48^e the contact 48. The end of the contact farthest removed from the pivotal point 48^e extends over the fusible plug 48^c. The insulated contact 49 is mounted upon the insulated plug 49^a mounted upon the pipe 48^a and the contact 49 has an electrical connection with the line wire 50. When the fusible plug 48^c is melted the force of the water flowing through the nozzles will move the contact 48 about the pivotal point 48^e and will close the circuit. The wiring of my improved system consists of a lead 50 which extends along one side of the series of supervised devices 5, and which in the example disclosed is connected with the switch arms 49. This lead 50 is connected at its end remote from the battery to switch arm 40. From contact 42 with which switch arm 40 engages, a lead 51 is connected therewith and with one terminal of magnet 3. The opposite terminal of magnet 3 is connected by means of a lead 52 with contacts 48 of the supervised devices 5 and with contact 43 of switch 14. Switch arm 41 of switch 14, which normally engages contact 43, is connected with a lead 53 extending to and connected with the negative pole of the battery. This series of connections comprises the normally closed circuit in which supervised devices 5 are connected in parallel.

The auxiliary circuit, previously mentioned, consists of a lead 54 connecting lead 52 and contact 47 of switch 16, a lead 55 which connects switch arm 46 of switch 16 and the positive pole of the battery, a lead 56 which connects the negative pole of the battery and switch arm 44 of switch 16, and a lead 57 which connects contact 45 and lead 51 of the normally closed circuit.

In describing the operation of my improved system I will first describe the action of the timing device and the transmitter upon the closing of the switches of supervised device 5, then I will describe the action of the system upon a breakage occurring in the circuit in which the switches of supervised devices 5 are located, and finally describe the action of the system upon breakage or other disarrangement of the battery 4.

In its normal condition it will be assumed that the system is as disclosed in the drawing, the timing device being restrained by the magnet 3 to permit the tripping lever 12 to occupy notch 10 of the transmitter so that the transmitter is held in its inoperative position. In this position of the timing device pin 29 is in engagement with the curved

edge of sector 30 and thus the end 21 of its pawl 20 is held from engagement with notches 10 or 11 of disc 9 and its member 23 held from engagement with branch 24 of finger 25. Signal sending circuit breaker 7 is in its normal condition closing circuit 8 and the teeth of signal wheel 6 are in position to transmit a signal immediately upon the transmitter being tripped. Switch 16 is held in its normal opened position by reason of the end of switch lever 44 occupying notch 15^a of cam 15 and switch 14 is normally in its closed position by reason of the end of its switch arm 40 occupying notch 13^a of cam 13. Tripping lever 12 has its shoulder 27 in engagement with branch 26 of finger 25 to lock pawl 17 to prevent operation of the transmitter. Each of the switches of supervised devices 5 is in a normally opened position.

When the system is operated by a flow through the extinguisher system with which it is connected, the following series of operations takes place. The normally closed circuit existing through the series of supervised devices 5 and through the signal system when it is in its normal condition as disclosed in the drawing, is as follows; the current flows from the battery through the positive pole thereof, through resistance R, which is inserted for the protection of the battery, through lead 50, switch arm 40, contact 42, lead 51, magnet 3, lead 52, contact 43, switch arm 41, and lead 53 back to the battery.

It will now be assumed that the switch of one of the supervised devices 5^a is closed by a flow through the extinguisher system. This causes switch arm 49 to engage contact 48 of the switch of the supervised device. Such an action causes magnet 3 to be short circuited and establishes a circuit as follows. From the positive pole of battery 4, through lead 50, switch arm 49, contact 48, lead 52, contact 43, switch arm 41, lead 53, and back to the battery. The result of thus short circuiting magnet 3 is that armature 33 is released to place weight 34 under direct control of the retarding mechanism 37 of timing device 2. As weight 34 lowers, end 32^a of lever 32 of the timing device engages end 28 of releasing lever 12 of the transmitter, and sector 30 simultaneously disengages pin 29. This releases ratchet 17 and permits operation of the transmitter. Detent 12^a of the releasing lever 12 being disengaged from notch 10, transmitter 1 then starts to operate so that its disc 9 rotates in the direction of arrow A, signal wheel 6 rotating in the direction of arrow B. Detent 12^a having been lifted from notch 10, the rotation of disc 9 places it upon the edge of the disc. Simultaneously with the rotation of disc 9 the end of switch arm 44 of switch 16 engages inclined shoulder 15^b of cam 15 and

causes switch arms 44 and 46 to engage the respective contacts 45 and 47. This establishes a new circuit through magnet 3, extending from the positive pole of the battery 4 through lead 55, switch arm 46, contact 47, lead 54, lead 52, magnet 3, lead 51, lead 57, contact 45, switch arm 44, lead 56, and back through the battery 4. However, magnet 3 is prevented from becoming energized by reason of the short circuit existing between the positive and negative poles of the battery over lead 50, the closed switch of supervised device 5^a, lead 52, contact 43, switch arm 41, and lead 53. Therefore, the transmitter continues to operate to cause its signal-sending circuit breaker 7 to transmit a signal as indicated by the series of signal teeth C, D, E, F, H, I, J, on signal wheel 6. As the signal wheel continues to rotate, notch 11 becomes positioned under detent 12^a but as magnet 3 is short circuited by the conditions that exist at the supervised device 5 the detent 12^a and notch 11 cannot engage and now the continued operation of the transmitter will cause the end of switch arm 40 to be lifted by the inclined shoulder 13^b to cause it to ride upon the edge of cam 13. This position opens the switch by lifting switch arms 40 and 41 from the respective contacts 42 and 43. Thus the short circuit existing at supervised device 5^a, is eliminated and magnet 3 is placed under the influence of the circuit established by the closing of switch 16 as previously described. This occurs just previous to the engagement of end 21 of pawl 20 with notch 10 of disc 9 of the transmitter. Magnet 3, having been energized just previous to the engagement of pawl 21 with notch 10, caused armature 33 to be retracted so that weight 34 is lifted. This places the edge of plate 30 under pin 29 of arm 22 of pawl 20 and prevents end 21 of pawl 20 entering notch 10. This prevents engagement of finger 23 with branch 24 of finger 25 of escapement pawl 17 so that the transmitter is permitted to continue its operation until cams 13 and 15 and disc 9 have made a complete revolution and then respective notches 13^a and 15^a are again normally positioned to cause the ends of switch arms 40 and 44 to be operated by them and permitting lever 12, to engage escapement pawl 17, by means of finger 25. The system is then placed in its normal condition by rewinding. This should not be done, however, until the supervised device at 5 has been repaired or restored to normal. During the aforesaid operation which required one complete revolution of cams 13 and 15 and disc 9 and of course, drive wheel 9^a, the signal wheel was caused to rotate many times, being the full capacity of the transmitter, which could be made any suitable number of rounds, as for instance, common practice might make this signal six rounds of

the signal, whereas for a broken wire, or a disabled battery a less number of rounds of the signal would be transmitted in a manner to be now described.

It will be assumed that, the system being in its normal condition, a break in the circuit occurs at a point designated by numeral 52^a. This causes magnet 3 to become de-energized to permit armature 33 to be released, whereby weight 34 will cause operation of the timing device 2. This causes end 32^a of lever 32 of the timing device, to be brought into engagement with end 28 of lever 12 of the transmitter to cause the transmitter to be released. Operation of the transmitter then causes the closing of switch 16 by bringing inclined shoulder 15^b under the end of switch arm 44 to cause switch arms 44 and 46 to engage the respective contacts 45 and 47, thus establishing a circuit from the positive pole of battery 4, through lead 55, switch arm 46, contact 47, lead 54, lead 52, magnet 3, lead 51, lead 57, contact 45, switch arm 44, and lead 56, back through the battery. Magnet 3 is then energized to retract armature 33 to permit detent 12^a of lever 12 to engage notch 11 as soon as it comes into engagement therewith. This brings the notched end of lever 12 into engagement with branch 26 of finger 25 to stop the operation of pawl 17 for the purpose of locking the transmitter against further movement. Thus one signal in accordance with teeth C, D and E of signal wheel 6, is transmitted by circuit breaker 7 to the central station. This indicates a broken line. As soon as the circuit is repaired the transmitter is rewound and the system is again in its normal condition. Now the distance from notch 10 to notch 11 permits signal wheel 6 to transmit the signal once and the distance notch 10 has to travel in order to engage end 21 of pawl 20 is such as to permit signal wheel 6 to transmit the signal twice. The next condition which might arise to disturb the system from its normal condition is a broken or disabled battery. Under this condition the magnet is either gradually or suddenly deenergized to release armature 33 so that weight 34 will cause operation of the timing device, thereby operating tripping lever 12 to release the transmitter. In addition to this, sector 30 is removed from engagement with pin 29 of arm 22 to permit pawl 20 to enter notch 10 as soon as it registers with end 21 of the pawl. In this condition notch 11 will pass detent 12^a without effecting its operation for the reason that lever 12, is positioned by member 32^a due to battery trouble so that it cannot engage said notch, therefore said notch will advance to a position under end 21 of pawl 20. This permits a second round of the signal from signal wheel 6 to be transmit- 130

ted and since pawl 21 is not under the control of plate 30, due to battery trouble, end 21 of said pawl will register with notch 10 and member 23 will engage finger 25 of escapement 17 thereby preventing further operation of the transmitter.

Having thus described my invention, what I claim is:

1. An electric signalling system for supervising automatic fire extinguisher systems, comprising a transmitter, a controlling lever operatively associated with the transmitter, and adapted to stop the transmitter, a pawl operatively associated with the transmitter and having means adapted to stop the transmitter at a period of operation different from that controlled by the lever, and an electromagnetically responsive means operatively connected with the extinguisher system to be supervised, whereby the lever and the pawl will be controlled for a change in conditions arising in the extinguisher system.
2. An electric signalling system for su-

30 pervising automatic fire extinguisher systems, comprising a signal transmitter, a transmitter controlling lever, a transmitter controlling pawl, a lever and pawl releasing mechanism having retarded motion, an electromagnetically controlled device for conditioning the retarded lever and pawl operating mechanism for controlling the operation of the transmitter for a change of condition in the extinguisher system to be supervised, said lever being adapted to control the transmitter in response to a change 35 of condition in the extinguisher system, said pawl being adapted to control the transmitter in response to a change in conditions in the signal system.

In testimony whereof, I have hereunto subscribed my name this 5th day of May, 1917.

JAMES D. NELSON.
